UNITED STATES PATENT OFFICE

CHARLES A. CAMPBELL, OF WATERTOWN, NEW YORK, ASSIGNOR TO THE NEW YORK AIR BRAKE COMPANY, A CORPORATION OF NEW JERSEY

SIGNAL SYSTEM

Application filed August 3, 1928. Serial No. 297,224.

This invention relates to pneumatic signal systems, and particularly to the type of system commonly used on railroad trains.

In such systems a signal pipe is normally maintained fully charged by a pressure reducing feed valve which is constantly operative, and which feeds air from a storage volume, which commonly is the main reservoir of the air brake system. The signal pipe is connected from car to car by suitable hose connectors, and on each car there is a so-called conductor's valve, which is merely a valve for venting the signal pipe to atmosphere for the purpose of producing in the signal pipe momentary reduced pressure impulses. These impulses traveling forward in the signal pipe, reach and actuate a signal valve in the cab, and this valve responds to each reduced pressure impulse to vent signal pipe air through a whistle. When the device functions properly the whistle blows a signal blast for each opening of a conductor's valve.

In trains of some length, say fifteen cars or over, the systems of the prior art commonly fail to function after a few blasts have been sounded, although the signal code involves as many as seven blasts. Failure after the second blast in long trains is a common occurrence. This failure is caused partly by faulty manipulation of the conductor's valve, i. e., the venting of too much air for each blast; partly by leakage from the signal pipe; and generally by any cause which serves to produce an undue reduction of signal pipe pressure. The difficulty is accentuated by the fact that the signal valve itself vents signal air to blow the whistle.

I have discovered that the important cause of the failure to operate is the opening of the feed valve, as a result of depleted signal pipe pressure. This valve opens for a very slight reduction of pressure and commonly functions to permit a pulsing feed flow. The positive pulsations thus produced in the brake pipe neutralize or interfere with the negative pulsations caused by the conductor's valve, and the result is that the signal valve does not respond properly.

The present invention overcomes this difficulty by the use of two novel mechanisms in

conjunction with signal systems otherwise of conventional form. While these two devices may be used singly, they produce the best results in conjunction with each other, and can be combined in a unitary structure.

The first of these mechanisms is put into action when the signal is actuated, and serves to prevent the feed valve from feeding air to the signal pipe. The mechanism preferably includes a timing device which causes the suspension of feeding to persist for a period longer than the normal interval between successive signal blasts. In this way feed flow is suspended throughout a series of successive blasts forming a code signal.

The second mechanism provides means for blowing the whistle by main reservoir air instead of by signal pipe air. It thus becomes possible to reduce the amount of air vented from the signal pipe by the signal valve and yet secure a stronger and more certain blast from the whistle.

Generally stated, the air discharged by the signal valve is caused to operate a diaphragm mechanism which controls the blowing of the whistle and which charges the timing reservoir. This timing reservoir has a vent which dissipates the charge in a given period of time, and while the charge persists its pressure acts upon an abutment to close a valve controlling the feed passage. This valve is preferably but not necessarily, distinct from the feed valve.

The preferred embodiment of the invention is illustrated in the accompanying drawing which shows, partly in elevation, and partly in vertical section, that portion of the signal equipment which is mounted on a locomotive. Only a portion of the signal pipe is shown and the conductor's valves, since they are of ordinary construction familiar to those skilled in the art have been omitted altogether.

The supply reservoir is shown at 1. The feeding flow from this reservoir occurs through a stop valve 2, normally open, an automatic pressure reducing feed valve 3, of ordinary construction, and a strainer 4, of ordinary construction.

In the conventional system this feed flow

would be directly to the signal pipe 5, which, as stated, extends throughout the train, being connected from car to car by hose connectors, one of which is shown at 6. In the present device, however, the feed controlling mechanism is interposed in the path of flow to the signal pipe 5, and this mechanism, as well as the signal valve, is supported on a bracket structure 7, which contains a relatively large timing reservoir 8 and a number of ports and passages hereinafter described.

Bolted to a ported face on the lower side of the bracket 7 and communicating with the chamber 8 by means of a passage 9 is a housing made up of two castings 11 and 12. This housing contains the feed interrupting valve proper. The pipe 13 which leads the air from the filter 4 communicates with a port 14 formed in the members 7, 11 and 12, and leading to the under side of a valve seat 15. From the space above this seat there leads a passage 16 which communicates with the signal valve hereinafter described. A branch pipe 17 serves as a connection from the signal pipe to the signal valve. A choke 18 is interposed in this connection in order to restrict the flow, and thus preclude over-stressing of the signal valve diaphragm, particularly while charging the device.

Mounted in the casting 11 is a cylinder bushing 21 which makes a close slip fit in the casting and is sealed by the gasket 22 which also seals the joint between the castings 7 and 11. Working in the cylinder 21 is a piston 23 having a through bleed port 24 which is the timing port through which the chamber 8 is vented after it has been charged. The space below the piston 23 is vented to atmosphere by the passage 25. The piston 23 is fast on a valve stem 26 which carries a valve 27 arranged to coact with the seat 15. The chamber 28, which is above the seat 15 and in communication with the passage 16, is isolated from the space below the piston 23 by a partition 29. This isolation is further maintained by the fact that when the valve 27 is in its upper position it seats and seals against a guide bushing 31 fixed in the partition 29. The piston 23 is urged upward to open the valve 27 by means of a coil spring 32 which surrounds the valve stem 26.

The normal condition of the parts is with the piston 23 in its upper position, the chamber 8 vented to atmospheric pressure, and the valve 27 open. The signal valve above alluded to includes a bracket portion 33 which is bolted to the member 7 and sealed thereagainst by means of a gasket 34, and the lower portion 35 which contains a balancing chamber or reservoir 36. The bracket member 33 is formed with a diaphragm chamber 37 and the chambers 36 and 37 are isolated from each other by a diaphragm 38 which also serves as a gasket between the parts 33 and 35. The diaphragm 38 carries a

pair of stiffener plates 39 which engage opposite sides of the diaphragm and are clamped together by a hub 41 and a nut 42. The hub is provided with an axial restricted port 43 into the lower end of which projects a tapered guide and throttling pin 44 fixed in the member 35. There is also a lateral port 45 which leads to the port 43 in the hub, and is smaller than port 43.

Hub 41 carries three pins 46, two of which are visible in the drawing, and these are designed to engage a disk or plate 47 fast on a check valve 48 which seats downward against the seat 49 and is held against chattering by a light spring 51. The valve 48 is guided by a stem which works in a guideway formed in the plug or cap 52. The port 16 after passing through the choke 18 connects with the chamber 37. The valve 48 controls flow from the chamber 37 to a port 53 which extends through the bracket member 33 and through the member 7. The port 53 communicates through a choke port 54 with an adjacent port 55 also formed in the member 7, and this port 55 communicates through pipe 56 with a signal whistle 57.

There is a by-pass connection 58 which leads from the reservoir 1, or, to be more accurate, from a point between the cock 2 and feed valve 3, to a passage 59 formed in the casting 7. Bolted to the casting 7, and sealed thereto by means of a gasket 61, is a housing 62 which contains extensions of the ports 53, 55, 59. It also contains an extension of port 63 which connects directly with the timing chamber 8 in the member 7.

Casting 62 is counterbored from its opposite sides to form seats for two opposed diaphragms 64 and 65. The space 66 between these two diaphragms is in direct communication with the passage 53. The diaphragms are clamped in place by supporting rings 67 and 68, which are identical in construction, and these clamping rings are held by spider nuts 69 and 71. The spider nuts are ported so that the space 72 below the diaphragm 66 communicates directly with the chamber 8, and the space 73 above the diaphragm 65 communicates directly with the passage 55. The spider nuts 69, 71, act as partitions between the chambers 72 and 73, on the one hand, and chambers 74 and 75, on the other hand. The chambers 74 and 75 are formed in caps 76 and 77 bolted to the member 62, and these chambers are in communication with branches of the passage 59 so that chambers 74 and 75 are always at the pressure existing in reservoir 1.

Each of the spider nuts 69 and 71 is provided with a check valve which controls flow from the chamber 74 to the chamber 72, or from the chamber 75 to the chamber 73 as the case may be. In the member 69

there is a seat bushing 78 with which coacts a check valve 79, having a guide stem 81 and a seating spring 82. This valve has a pilot 83 which abuts against a bearer plate 84 seated against the diaphragm 64. Similarly a seat bushing 85 is mounted in the spider 71 and with this coacts the valve 86 having a stem 87 and seating spring 88. The pilot is shown at 89 and coacts with the bearer plate 91 which seats against the diaphragm 65.

With the parts so arranged, let us assume that all conductor's valves are closed, and that reservoir 1 is charged. The system will be charged as follows: Main reservoir air will flow directly through the pipe 58 and charge the chambers 74 and 75 to reservoir pressure. At the same time flow will occur with a reduction of pressure through the feed valve 3, strainer 4, pipe 13, passage 14, passage 16 to the signal pipe 5, charging this to the desired pressure, say fifty pounds per square inch. At the same time restricted flow will occur through the choke 18. This pressure will tend to depress the diaphragm 38, but the effect of the choke 18 is such as to prevent overstressing of the diaphragm. Once the chamber 37 has been partly charged flow will commence from the passages 43 and 45 to charge the chamber 36. With these conditions valve 48 will be closed and the space 66 between the diaphragms 64 and 65 will be vented to atmosphere by way of choke 54 and whistle 57. Chamber 8 will remain at atmospheric pressure which is established through the vent port 24.

Upon a proper reduction of pressure in the pipe 5, such as would be created by a manipulation of the conductor's valve, a wave of reduced pressure will be caused to move forward in the pipe 5 and pass through the branch 17 to the space 37 above the diaphragm 38. Because of the throttling action of the part 45 diaphragm 38 will immediately move upward, unseating valve 48, but this unseating action will be momentary only because of the increased passage offered through 43 when the diaphragm moves upward. Obviously, therefore, the diaphragm will immediately resume its normal position, allowing valve 48 to close. However, the momentary opening of valve 48 allows signal pipe air to flow by passage 16, choke 18, valve seat 49 and passage 53, to the chamber 66 between the diaphragms 64 and 65. The pressure in the chamber 66 will persist until dissipated by leakage through the small choke 54. While the pressure in 66 persists the diaphragms will be forced apart, unseating the valves 79 and 86. The unseating of valve 86 allows reservoir air to flow from the chamber 75 by way of chamber 73, passage 55 and pipe 56, to the whistle 57, which sounds a sharp and clearly audible blast. The unseating of valve 79 allows res-

ervoir air to flow by way of chamber 72 and passages 63 to the timing chamber 8, which it charges.

The result of the increased pressure in chamber 8 is the depression of the piston 23 and consequently the seating of the valve 27. The valve 27 will be held closed until the bleed port 24 has vented the chamber 8 sufficiently to permit the spring 32 to force the piston upward. The parts are so dimensioned that the period of persistence will be several seconds, say two or three seconds longer than the normal interval between signal blasts.

Since the chamber 8 is charged for each blast it follows that after the first blast, and for a definite period after the last blast, the valve 27 will be held closed. This will preclude, during the entire signal period, the feeding of any air to the signal pipe 5. However, the total volume of the signal pipe is sufficient to furnish the necessary air to actuate the signal valve. The practicability of the scheme, however, is greatly enhanced by the fact that the signal valve does not vent from the signal pipe sufficient air to blow the whistle 57, but vents merely the decidedly smaller quantity necessary to charge the chamber 66. The signal can be repeatedly operated in the manner described, and the possible number of blasts therefore exceeds any requirements of service. None-the-less the gradual depletion of pressure in the signal pipe 5, which is a necessary incident to the repeated successive blasts, does not affect the loudness of the signal given by the whistle 57, for the reason that the whistle is blown by main reservoir air and not by signal pipe air.

While I have described one embodiment in particular detail, I do not imply that the invention is necessarily limited to this embodiment, and contemplate possible modifications within the scope of the appended claims. While systems of this sort are ordinarily operated by air, it is apparent that analogous pressure fluids might be used, and no limitation to air alone is implied.

What is claimed is:

1. The combination with a signal system of the type including a signal pipe, automatic means for feeding pressure fluid thereto, a signal device and valve means actuated by a depression of signal pipe pressure to actuate the signal device; of means actuated by such depression of signal pipe pressure for temporarily suspending the feeding function of said pressure fluid feeding means.

2. The combination with a signal system of the type including a signal pipe, automatic means for feeding pressure fluid thereto, a signal device and valve means actuated by a depression of signal pipe pressure to actuate the signal device; of means actuated by such depression of signal pipe pressure for temporarily suspending the feeding function of said pressure fluid feeding means; and a tim-

- ing device to cause said suspension to persist for a definite period.
3. The combination with a signal system of the type including a signal pipe, automatic means for feeding pressure fluid thereto, a signal whistle and a signal valve device actuated by a depression of signal pipe pressure, of means controlled by said signal valve device for blowing said whistle by means of pressure fluid from a source other than the signal pipe; and means also controlled by the operation of said valve device to suspend temporarily the feeding function of said pressure fluid feeding means.
4. The combination with a signal system of the type including a signal pipe, automatic means for feeding pressure fluid thereto, a signal whistle and a signal valve device actuated by a depression of signal pipe pressure, of means controlled by said signal valve device for blowing said whistle by means of pressure fluid from a source other than the signal pipe; means also controlled by the operation of said valve device to suspend temporarily the feeding function of said pressure fluid feeding means; and a timing device to cause said suspension to persist for a definite period.
5. In a signal system, the combination of a supply reservoir; a signal pipe; a pressure-maintaining feed valve interposed between said reservoir and pipe; a signal valve operable by a depression of signal pipe pressure to vent pressure fluid from the signal pipe; a signal whistle; and valve means operable by said vented fluid to connect said reservoir with the whistle.
6. In a signal system, the combination of a supply reservoir; a signal pipe; a pressure-maintaining feed valve interposed between said reservoir and pipe; a signal valve operable by a depression of signal pipe pressure to vent pressure fluid from the signal pipe; a signal whistle; and valve means operable by said vented fluid to connect said reservoir with the whistle and interrupt flow through the feed valve.
7. In a signal system, the combination of a supply reservoir; a signal pipe; a pressure-maintaining feed valve interposed between said reservoir and pipe; a signal valve operable by a depression of signal pipe pressure to vent pressure fluid from the signal pipe; a signal whistle; valve means operable by said vented fluid to connect said reservoir with the whistle and interrupt flow through the feed valve; and timing means for causing said interruption to persist.
8. In a signal system, the combination of a supply reservoir; a signal pipe; a pressure-maintaining feed valve interposed between said reservoir and pipe; a signal valve operable by a depression of signal pipe pressure to vent pressure fluid from the signal pipe; a valve operable by said vented fluid to connect
- said reservoir with said whistle; a timing chamber having a bleed port; a second valve operable by said vented fluid to charge said timing chamber from said reservoir; and a pressure actuated valve controlling flow through said feed valve and arranged to be held closed by pressure in said vented timing chamber.
9. The combination with a signal system of the type including a signal pipe, a storage reservoir, a pressure-maintaining feed valve for feeding pressure fluid from the reservoir to the train pipe, and a signal valve operable by a reduction of signal pipe pressure to vent pressure fluid from the signal pipe, of a timing chamber having a bleed port; a valve operable by said vented fluid to charge said timing chamber from said reservoir; and a pressure actuated valve controlling flow through said feed valve and arranged to be held closed by pressure in said timing chamber.
- In testimony whereof I have signed my name to this specification.
- CHARLES A. CAMPBELL.
